DESIGN FOR A BOTTLE

William Guyer, New York, N. Y., assignor to
Joseph E. Seagram & Sons, Inc., Lawrenceburg,
Ind., a corporation of Indiana

Application June 8, 1935, Serial No. 57,198

Term of patent 14 years

To whom it may concern:

Be it known that I, William Guyer, a citizen of the United States, residing at New York, county of New York, and State of New York, have invented a new, original, and ornamental Design for a Bottle, of which the following is a specification, reference being had to the following drawing, forming a part thereof.

The ornamentation shown in Figure 1 is identical on the three sides of the bottle, that is the two sides and the rear. Figure 2 is a different view, disclosing the front of the bottle.

I claim:

The ornamental design for a bottle as shown and described.

WILLIAM GUYER.
